[57] CLAIM

The ornamental design for a flapper valve housing for a concrete pump or the like, substantially as shown.

DESCRIPTION

FIG. 1 is a top plan view of the flapper valve housing for a concrete pump, or the like, showing my new design;

FIG. 2 is a front elevational view thereof;

FIG. 3 is a bottom plan view thereof;

FIG. 4 is a rear elevational view thereof;

FIG. 5 is a right side elevational view thereof;

FIG. 6 is a left side elevational view thereof; and

FIG. 7 is a sectional view taken on line 7—7 of FIG. 1.

FIG. 1.

FIG. 2.

*FIG. 3.**FIG. 4.**FIG. 5.**FIG. 7.**FIG. 6.*
